UNITED STATES PATENT OFFICE.

JAMES JARVIS PREEBLE, OF NEWTON, MASSACHUSETTS; LIVINGSTON STEBBINS, ADMINISTRATOR OF SAID JAMES J. PREEBLE, DECEASED, ASSIGNOR TO SPRACO, INC., OF SOMERVILLE, MASSACHUSETTS, A CORPORATION OF MASSACHUSETTS.

SPRAY NOZZLE.

Application filed May 21, 1926. Serial No. 110,600.

The present invention relates to spray nozzles, and more particularly to spray nozzles for use in a spray cooling system such as a cooling pond.

5 Cooling pond spray nozzles are usually of two types. In one type the spray discharged from the nozzle forms an inverted cone having the spray drops distributed therethrough in a homogeneous manner. In the other type of 10 spray nozzle the inverted cone formed by the discharged spray is hollow. In the hollow cone type of spray nozzle the water enters the nozzle in a direction normal to the direction the water takes in passing out of the 15 nozzle. During its passage through the nozzle all the entering water is subjected to a centrifugal or whirling action. The spray discharged from spray nozzles of the hollow cone type heretofore proposed is lop-sided, 20 that is, the spray is heavier on one part of the cone than on another part. This proves conclusively that such spray nozzles do not produce that uniform distribution of the spray necessary to obtain the maximum cooling efficiency. 25 I have determined that the lop-sided spray obtained in the spray nozzles of the hollow inverted cone type heretofore proposed is due to the fact that all the water which is subjected to a centrifugal or whirling 30 action in the nozzle collides at about the end of its first whirl with all the water in the stream entering the nozzle.

The object of the present invention is to 35 produce a spray nozzle of the inverted hollow cone type by which a uniform distribution of the drops of spray throughout the area of the inverted hollow cone may be obtained.

To the accomplishment of this object, a feature of the present invention contemplates 40 the provision, in a spray nozzle having an outlet, an intake through which the liquid enters the nozzle in a direction normal to the direction which the liquid takes in passing out through the outlet, and means for subjecting all the entering liquid to a centrifugal 45 or whirling action, or means for elevating the entering liquid before and during its first whirl above the lowest level of the entering liquid.

50 Broadly considered the whirling liquid may be elevated during its first whirl above the lowest level of the entering liquid in any manner found desirable or expedient as any elevation of the whirling liquid improves the

55 spray over that of the hollow inverted cone type of spray nozzles heretofore proposed. I prefer, however, to elevate the whirling liquid at about the end of its first whirl somewhat above the mean level of the stream of entering liquid as I then obtain just the 60 proper mixture between the whirling liquid and the entering liquid to produce a uniform distribution of the spray drops throughout the area of the hollow inverted cone.

In addition to the features of the invention above referred to other features of the invention consist in certain devices, combinations and arrangements of parts as fully set forth hereinafter, the advantages of which will be readily understood by those skilled in 70 the art.

The various features of the present invention will be readily understood from an inspection of the accompanying drawings illustrating the best form of the invention at present known to the inventor, in which,

75 Figure 1 is an elevation of the spray nozzle;
Fig. 2 is a central sectional elevation;

Fig. 3 is a sectional plan, and

Fig. 4 is a right side sectional elevation on 80 the line 4—4, Fig. 1.

Referring to the drawings the spray nozzle comprises a hollow cylindrical shell 5 having a roof 6 and a floor 7. The roof 6 is provided with an aperture or outlet 8 through 85 which the liquid introduced into the shell 5 is discharged. In one wall of the shell adjacent the floor 7 a gap 9 (Fig. 3) is formed through which the liquid to be discharged enters the shell both in a direction normal to the direction the liquid takes in passing out of the shell through the outlet 8 and in a direction substantially tangential to the periphery of the shell so that all the entering liquid is subjected by the shell to a centrifugal or whirling 90 action.

95 On one side of the gap 9 the shell 5 is provided with a wall 10 (Fig. 3) which extends laterally from the shell in a direction substantially tangential to the periphery of the 100 shell. On the other side of the gap 9 the shell 5 is provided with a wall 11 (Figs. 1, 3 and 4) which is extended laterally away from the shell on a curve reverse to that of the shell. The walls 10 and 11 merge above and below 105 the gap 9 to form a hollow cylindrical boss forming an intake 12 having internal threads 13 therein to facilitate connection of the

spray nozzle to a distributing pipe (not shown).

Part of the liquid entering the intake 12 is diverted by the wall 11 towards the wall 10. 5 The rest of the liquid, and that portion of the liquid diverted towards the wall 10 by the wall 11, is conducted by the wall 10 into the shell 5 through the gap 9 both in a direction normal to the direction the liquid takes in 10 passing out of the shell through the outlet 8 and in a direction tangential to the periphery of the shell 5. The entering liquid thus is subjected by the cylindrical wall of the shell 5 to a centrifugal or whirling action. 15 The floor 7 of the shell is provided with a channel 14 (Fig. 2) of a width substantially half the width of the minor axis of the shell 5. One end of the channel terminates at the threads 13 of the intake (Fig. 4). The other 20 end of the channel terminates at an elevated shelf 15 (Figs. 1, 3 and 4) near the juncture of the wall 11 with the shell 5. Between its terminals the channel is formed as a ramp 16 so that as the whirling liquid flows around 25 the periphery of the shell on its first whirl all the whirling liquid is elevated by the ramp 16 towards the outlet 8 (see the arrow of Fig. 4). Rising centrally from the floor 7 in the major axis of the shell 5 is a post 17 around which the whirling liquid flows on 30 its first whirl.

As shown in Fig. 1 the height of the shelf 15 is just above the mean level of the entering liquid. With this construction the lower 35 portion only of the whirling liquid at about the end of its first whirl collides with the upper portion only of the entering liquid. I find that with this arrangement the correct amounts of whirling liquid and entering 40 liquid are mixed to produce a spray the drops of which are uniformly distributed over the area of the spray discharged through the outlet 8 in a hollow inverted cone. In addition to its beneficial function of lifting the whirling liquid above the mean level of the entering liquid the ramp also initiates the upward 45 spiral movement of the whirling liquid towards the outlet 8.

It must be understood that while I have employed specific terms in describing the best embodiment of my invention known to me these terms are used in a generic and descriptive sense and not for purposes of limitation, the true scope of the invention being set forth in the following claims. 50 55

What is claimed as new, is:

1. A spray nozzle having, in combination, a shell or casing having an outlet and an intake through which the liquid enters the shell in a direction normal to the direction the liquid takes in passing through the outlet, means to subject all the entering liquid to a centrifugal or whirling action, and means for elevating all the whirling liquid during its first whirl above the mean level of the entering liquid including a floor on one end face of the shell having terminals on different levels connected by a ramp, the level of one of the terminals being intermediate the mean and highest level of the entering liquid. 60 65 70

2. A spray nozzle having, in combination, a shell or casing having an outlet and an intake through which the liquid enters the shell in a direction normal to the direction the liquid takes in passing through the outlet, means to subject all the entering liquid to a centrifugal or whirling action, and means for elevating the lower portion of the whirling liquid to a level at about the end of its first whirl above the mean level of the entering 80 liquid and below the highest level of the entering liquid. 75

3. A spray nozzle having, in combination, a shell or casing having an outlet and an intake through which the liquid enters the shell 85 in a direction normal to the direction the liquid takes in passing through the outlet, means to subject all the entering liquid to a centrifugal or whirling action, and means for colliding the lower portion only of the 90 whirling liquid at about the end of its first whirl with the upper portion only of the entering liquid.

In testimony whereof I have signed my name to this specification.

JAMES JARVIS PREBLE.
